UNITED STATES PATENT OFFICE

WILLIAM D. HAILES, OF ROCHESTER, NEW YORK, ASSIGNEE TO GENERAL RAILWAY SIGNAL COMPANY, OF ROCHESTER, NEW YORK

CONTINUOUS INDUCTIVE TRAIN-CONTROL SYSTEM

Application filed July 18, 1929. Serial No. 379,154.

This invention relates in general to electric filters, and has more particular reference to a filter for use in continuous inductive alternating current train control systems, either of the uncoded type, or of the coded type, such as disclosed in the application of W. D. Hailes, Ser. No. 228,058, filed October 22, 1927, for "Continuous train control systems."

In train control systems of the type referred to, it is usual to employ alternating train control current of a frequency different from the usual commercial frequencies, such for example as 100 cycles per second, whereby to avoid interference, by currents of other frequencies with the car-carried receiving apparatus. Also, in order to insure against such interference, a filter circuit can be employed in connection with the receiving car-carried apparatus for filtering out or suppressing, or both, currents of other than train control frequency.

In connection with coded continuous systems, it is desirable to have means for preventing oscillations produced by the coded current in the receiving apparatus and connected circuits from continuing too long, in order to prevent interference with the proper response of the car-carried apparatus to the particular code being received.

With the above and other considerations in view, it is proposed, in accordance with the present invention, to provide an improved filter circuit for use in train control systems.

Further objects, purposes and characteristic features will appear as the description progresses, reference being made to the accompanying drawing, showing in a wholly diagrammatic manner, and in no manner in a limiting sense, one form which the invention can assume. In the drawing:

The single figure of drawing is a diagrammatic representation of a filter circuit in accordance with the present invention.

Referring to the drawing, there is here shown a pair of track rails 1, through which train control currents flow as indicated by the arrows 2, with car-carried receiving coils *Rec* positioned above, and in inductive rela-

tion to, the rails, whereby to have voltages induced therein by the train control current.

The receiving coils *Rec* are connected up in series so as to have their induced voltages cumulative, and are connected across the primary *P*, of a loose coupled transformer *T*, the primary having a plurality of taps *a*, *b*, *c* and *d* whereby to permit varying the number of turns in the primary winding at will.

The circuit connecting up the receiving coils with the primary of transformer *T* includes, in series, the two receiving coils *Rec*, a resistance *R*¹, a resistance *R*², the primary *P* of the transformer *T*, a choke coil *X*, a condenser *C*³, and a condenser *C*⁴. The constants of this circuit have been chosen so as to pass currents of 100 cycles with less alternation than currents of either higher or lower frequencies. By this choice of constants the circuit acts so as to permit relatively large currents of 100 cycles to flow through the primary of transformer *T*, and to permit only relatively small currents of frequencies other than 100 cycles to flow through the primary of transformer *T*. Hence when the receivers are excited by 100 cycle current this circuit passes 100 cycle exciting current on to the transformer *T*; when receivers are excited by currents of other than 100 cycles this circuit alternates the currents transmitted to the transformer, and when 100 cycle and also other frequency currents are present under the receivers this circuit automatically passes on the 100 cycle current and alternates the currents of the other frequencies.

Since only 100 cycle current is permitted to flow to any great extent in the primary of transformer *T* the only voltage generated to any great extent in the secondary of transformer *T* will be of 100 cycles. Also since there is loose coupling between primary and secondary of transformer *T*, the small voltages other than 100 cycles will be unable to produce any appreciable current in the secondary, but the 100 cycle voltage generated in the secondary will cause a large secondary current because *C*⁴ is adjusted to enhance the effect of 100 cycle voltage and to diminish the effects of other voltages. Therefore the effect of 100 cycle rail current is to produce

a relatively large 100 cycle voltage across the condenser C^4 and the effect of currents of other than 100 cycles is alternated so greatly as to be negligible.

5 The secondary S of transformer T is connected in series with a resistance R^3 , across a condenser C^4 to constitute a circuit tuned to resonance at the frequency of the train control current and including in series the secondary S, the resistance R^3 and the condenser C^4 .

10 Connected across the condenser C^4 is an amplifier A, to the output side of which is connected a load L, such load being for example a coding primary relay or the like, as used in the Hailes application above referred to. The amplifier A preferably includes electron tube means with the usual grid filament circuit connected across condenser C^4 .

15 20 The transformer T, as stated above, is loose coupled by means of having a poor magnetic path coupling the primary and secondary turns, or by having the primary turns relatively few with respect to the secondary turns on a good magnetic circuit, or both. In this manner, the voltage across the secondary winding S can be adjusted by adjusting the number of turns included in the primary winding. Due to the loose coupling, if 25 the number of turns in the primary winding be increased, the voltage across the secondary winding likewise increases.

30 35 In the filter circuit just described, it was found desirable to make the inductance of the choke coil X approximately equal to the inductance of the two receiving coils Rec in series.

40 45 The loose coupled transformer T is employed to provide additional selective ability in the apparatus and provide a ready means of controlling the overall sensitivity of the complete circuit, and to deliver the filtered receiver energy to the amplifier at a suitable voltage. This control is accomplished by means of the primary having the several taps as described above, and the additional selectivity is obtained by virtue of the condenser C^4 which is adjusted, as set forth above, so that, for the desired frequency, maximum voltage appears at the terminals of the transformer secondary S.

50 55 The resistances R^1 , R^2 and R^3 are not required for filtering action but are used for the purpose of fixing the rate at which oscillations set up in the circuits will die out on removal of excitation, and are useful where the filter is to operate as a part of a coded type of control, such as described in the Hailes application above referred to. Rather than including these resistances in the receiving coils Rec , they are constituted by separate units which can be inserted or removed as required, the receiving coils being made so as to include no unnecessary resistance. In this manner the filter circuit

minus the various resistances R^1 etc., can be employed to advantage in connection with uncoded systems, while the circuit as shown can be employed in connection with coded systems, with the receiving coils Rec the same 70 in each case.

75 The above rather specific description of one form of device embodying the present invention has been given solely by way of illustration, and is not intended, in any manner whatsoever, in a limiting sense. Obviously, this invention can assume many different physical forms, and is susceptible of numerous modifications, and all such forms and modifications are desired to be included 80 by this invention, as come within the scope of the appended claims.

85 Having described my invention, I now claim:—

1. In a filter circuit for use in train control systems, in combination, a receiving coil, a loose coupled transformer, a series circuit connecting the primary of the transformer to the receiving coil and including tuning means for tuning the circuit to resonance at a desired frequency, a condenser connected across the secondary of the transformer for tuning the circuit including the secondary and the condenser to resonance at the desired frequency, a shunt connection 90 across the receiving coil for shunting other than the desired frequency around the primary of the transformer, and resistance insertable in the primary and the secondary 95 tuned circuits for adjusting the rate of decay of oscillations after excitation has ceased, for adapting the filter for use in coded train control systems.

100 2. In a filter circuit for use in train control systems, in combination, a receiving coil, a loose coupled transformer, a series circuit connecting the primary of the transformer to the receiving coil and including tuning means for tuning the circuit to resonance at a desired frequency, a condenser connected across the secondary of the transformer for tuning the circuit including the secondary and the condenser to resonance at the desired frequency, a shunt connection across the receiving coil for shunting other than the desired frequency around the primary of the transformer, and a plurality of taps on the primary of the transformer whereby to permit adjusting the ratio of primary to secondary turns for adjusting the overall sensitivity of the filter and the voltage across the transformer secondary.

115 120 125 3. In a filter circuit for use in train control systems, in combination, a receiving coil, a loose coupled transformer, a circuit connecting the primary of the transformer to the receiving coil and including tuning means for tuning the circuit to resonance at a desired frequency, a condenser connected across the secondary of the transformer for tuning

the circuit including the secondary and the condenser to resonance at the desired frequency, a shunt connection across the receiving coil for shunting other than the desired frequency around said primary of the transformer, resistance means insertable in the primary and secondary tuned circuits for adjusting the rate of decay of oscillations after excitation has ceased, for adapting the filter for use in coded train control systems, and a plurality of taps on the primary of the transformer whereby the permit adjusting the ratio of primary to secondary turns for adjusting the overall sensitivity of the filter and the voltage across the transformer secondary.

15 In testimony whereof I affix my signature.
WILLIAM D. HAILES.
